[57] CLAIM

The ornamental design for a fluorescent light adapter, as shown and described.

DESCRIPTION

FIG. 1 is a top plan view of the first embodiment of the fluorescent light adapter of the present invention;

FIG. 2 is a front elevational view thereof, the broken lines being shown for illustrative purposes only and forming no part of the claimed design;

FIG. 3 is a right side elevational view thereof, which is a mirror image of the left side;

FIG. 4 is a rear elevational view thereof;

FIG. 5 is a bottom plan view thereof; and,

FIG. 6 is a right side elevational view of an alternative embodiment of the fluorescent light adapter with a shorter neck, the embodiment otherwise being the same as the embodiment of FIGS. 1-5.
